UNITED STATES PATENT OFFICE.

ARTHUR R. BALL, OF MELVERN, KANSAS.

ADDING-MACHINE.

1,193,858.

Specification of Letters Patent.

Patented Aug. 8, 1916.

Application filed March 4, 1916 Serial No. 82,132.

To all whom it may concern:

Be it known that I, ARTHUR R. BALL, a citizen of the United States, residing at Melvern, in the county of Osage and State 5 of Kansas, have invented a certain new and useful Improvement in Adding-Machines, of which the following is a specification.

My invention relates to improvements in adding machines.

10 The object of my invention is to provide an adding machine which is simple in construction, which may be readily used by an inexperienced person, which is cheap to manufacture, is durable and not liable to 15 get out of order.

The novel features of my invention are hereinafter fully described and claimed.

In the accompanying drawings which illustrate my invention, Figure 1 is a perspective view of the preferred form of my invention, when used for the addition of a plurality of columns of figures. Fig. 2 is an enlarged front view of a portion of the machine shown in Fig. 1. Fig. 3 is vertical 25 sectional view of the machine shown in Fig. 1. Fig. 4 is an edge view of a portion of one of the disks of the machine shown in the preceding figures. Fig. 5 is a vertical sectional view on the line 5—5 of Fig. 3. 30 Fig. 6 is a front view, partly broken away, of a modified form of my invention, when employed to add a single column of figures. Fig. 7 is a central cross section of the same. Fig. 8 is a front view of the disk shown in 35 Figs. 6 and 7.

Similar reference characters designate similar parts in the different views.

Referring to Figs. 1 to 5, 1 designates a casing having an arcuate top provided with 40 a plurality of slots 2, through which are adapted to be inserted stop pins 3 adapted to enter radial holes 4 in a plurality of disks 5, corresponding in number to the columns to be added, and rotatable on a 45 shaft 6, the ends of which are respectively mounted in the sides of the casing 1. The lower ends of the slots 2 serve as stops for the pins 3, when the latter are mounted in the holes 4 and the disks 5 are moved in 50 the adding operation. For retracting the disks 5, each disk may be provided with a peripheral flange 7 having a peripheral notch 8 and extending through a slot 9 provided therefor in the casing 1. The 55 notch 8 is provided so that the operator may have means for being informed by the

sense of touch as well as sight, when the disk has been retracted beyond the initial or starting point. If desired, the notch 8 may be dispensed with. Respectively adjacent to and disposed along side of the row of holes 4 of each disk are numerals from zero to one hundred and nine inclusive, arranged in numerical order, one numeral for each hole 4, the holes 4 being one hundred and ten in number. The casing 1 is provided with a plurality of observation openings 10 arranged so as to have the numerals, designated by A, pass opposite to the openings 10 respectively. Respectively adjacent to the slots 2 are a series of rows of characters comprising digits B arranged in numerical order and spaced apart the same distance as the spacing between the adjacent holes 4.

In the upper front part of the casing 1 and respectively adjacent the characters B, at the left, as viewed in Figs. 1 and 2, are a plurality of holes 11 adapted to receive a marking pin 12, Fig. 1. In the operation of 75 this form of my invention, the disks 5 from right to left, as viewed from the front of the machine, respectively represent units, tens and hundreds. In adding a lot of numbers, the disks 5 are first set in the initial 80 position, in which the zeros of the numerals A will respectively show through the observation openings 10. A stop pin 3 is then inserted in the hole 4 of the unit disk 5, which hole is adjacent to the character B 85 corresponding to the first unit of the column of figures to be added. The stop pin is then employed to turn the unit disk until the pin strikes against the lower end of the slot 2 through which the pin extends. 90 The stop pin is then withdrawn, after another stop pin 3 has been inserted in the hole 4 which is adjacent to the digit B corresponding to the next unit in the column which is being added. The last stop pin is 95 then used to turn the unit disk until the stop pin strikes against the lower end of the slot 2 through which the pin extends. In this manner, the stop pins 3 are employed to turn the unit disk until all the figures in 100 the unit column have been added by the step by step turning of the disk in the manner just before described. At this time, the sum of the figures in the unit column which has been added will appear at the observation opening 10 opposite the unit disk 5, 105 providing the sum of the figures in the unit

column is one hundred and nine or less. If the sum of the units is less than one hundred, a stop pin 3 is inserted in a hole 4 of the tens disk, which hole is opposite the digit B of that disk corresponding to the numeral in the tens column of the number appearing at the observation opening of the unit disk. The tens disk is then turned by its stop pin until the pin strikes the casing 10 at the lower end of the slot 2 which is opposite the tens disk. The tens column of the numbers to be added is then added on the tens disk in the same manner as were the figures in the units column. If the sum 15 appearing at the observation opening 10 opposite the tens disk is less than one hundred, another stop pin 3 is inserted in the hole 4 of the hundreds disk which hole is adjacent to the digit of the row B corresponding to the left hand figure appearing at the observation opening 10 which is opposite to the tens disk. The last named stop pin is then used to turn the hundreds disk to a position in which the stop pin will strike 20 the casing at the lower end of the slot 2 which is opposite to the hundreds disk. The hundreds column of the numbers to be added is then added upon the hundreds disk in the manner the units and tens columns 25 30 were added on the units and tens disk. The sum of the figures which have been added may now be ascertained by an inspection of the numbers appearing at the three observation openings 10. In so doing, all of 35 the figures appearing in the hundreds observation opening 10 are considered, but only the right hand figures of the numbers appearing at the other two openings 10 are considered. Thus, if the three numbers appearing respectively at the three observation 40 openings 10 are 33, 43 and 31, the sum of the numbers added will be 3,331. In case that the number appearing in the observation opening opposite the units disk is 100 45 or over, the hundreds disk may be turned forwardly a distance of one hole. In case that the sum of the units in a column of figures is greater than 109, the operator, in turning the units disk, will turn said disk 50 until its observation opening shows a number between 100 and 109 inclusive, as, for example, 105. He will then advance the hundreds disk one hole, or the tens disk ten holes, and turn the units disk to a position 55 in which the numeral 5 will show at the units observation opening, following which the addition of the unadded figures in the units column will be continued as explained. 60 As shown in Figs. 2 and 4, the slot 2 is of such a length that it will equal the length of the blank space plus space occupied by ten holes in the periphery of the disk. Thus if the numeral showing at the observation opening is 100 or over, and the operator in 65 adding the column finds no hole opposite the

character designating the next numeral to be added, he will know that the maximum has been exceeded, will indicate on the next disk that 100 has been counted, and then will insert the stop pin in the uppermost 70 hole in the slot 2 and will turn the disk until the stop pin strikes the lower end of the slot at which time, the proper unit above 100 will appear at the observation opening. He will then proceed as already described 75 with the addition of the remaining figures in the column. As an additional example, assuming that in adding a column, the operator, in adding a column of figures, has operated the units disk, until, without his having taken notice of it, the observation opening will show the numeral 99. The next figure in the column to be added, we will assume is 9. He will insert the stop pin in the hole opposite the character 9 in the series B 80 and will then turn the disk until the stop pin strikes against the lower end of the slot 2, at which time the numeral 108 will appear at the observation opening. The operator, still taking no notice of what appears at the 85 observation opening, will then try to add the next figure in the column, which, we will assume, is 5. He will find no hole in the disk opposite the character 5 in the series B, so will know that the amount already added 90 exceeds 100, and will so indicate on the tens disk. Then he will insert the stop pin in the uppermost hole of the slot 2 and will turn the disk until the stop pin strikes the lower end of the slot, at which time the 95 numeral 8 will present itself at the observation opening, following which he will insert the stop pin in the hole 5 of the series B and will turn the disk until the stop pin strikes the lower end of the slot, and will 100 then continue the addition in the manner already described. It will thus be seen that by having the slot 2 of the proper length, relative to the blank space and the spaces occupied by the peripheral holes in the disk, 105 the operator may make the additions without having to perform any mental additions or subtractions, and without having to pay any attention whatever to what numerals appear at the observation opening. The addition will thus be a matter almost purely mechanical and will require very little mental effort. In like manner, when, in adding the tens column of figures, the number showing 110 in the tens observation opening 10 is between 100 and 109 inclusive, and there are more tens to be added, the hundreds disk is advanced ten holes, and the tens disk then turned to the numeral on the disk corresponding to the right hand figure showing in the observation 115 opening, following which the addition of the remaining figures in the tens column is proceeded with in the manner already described. When the total amount added exceeds 10,999, the pin 12, Fig. 1, may be in- 120 125 130

serted in the holes 11 for the purpose of marking up tens of thousands, each of said holes representing 10,000. In such case, only the right hand figure in the hundreds observation opening 10 is considered in reading the result, just as only the right hand figures appearing at the units and tens observation openings are considered. If desired, the holes 11 may be considered as representing only 1000 each, when the total amount of the sum of the numbers added is less than 11,000. If the holes 11 be considered as having a value of 1000, only the right hand figure in the hundreds observation opening is to be considered in reading the result. For the purpose of preventing interference between the disks 5 when they are turned, they may be separated from each other by means of spacing collars 13 secured upon the shaft 6, Fig. 3.

Referring to Figs. 6, 7 and 8, 14 designates a rectangular casing, in which is rotatably mounted a shaft 15 having secured thereto a thumb button 16. Secured to the shaft 15 and rotative therewith is a disk 17, which is provided with an arcuate row of transverse holes 18, which are adapted to pass in front of an arcuate slot 19 in the front of the casing 14 and concentric with the shaft 15. Adjacent to the holes 18 respectively are a like number of numerals numbering from zero to one hundred and nine inclusive. These numerals are adapted to consecutively appear, when the disk 17 is turned, at an observation opening 19, Fig. 6. In the front of the casing 14 are a series of holes 20, Fig. 6, which are adapted to receive a marking pin 21. Each of these holes represents a value of 100. Respectively adjacent to the holes 20 are numerals representing the respective value in hundreds of said holes. These numerals are designated by C. The numerals on the disk 17 are designated by D. Respectively adjacent to the slot 19 is a row of numerals comprising the digits. These numerals are designated by E and they are spaced apart the same distance as are the holes 18. The disk 17 may be turned, in operating the machine, by inserting in the holes 18 through slot 19, a pin 22, Fig. 6.

In making an addition, the disk 17 is turned to the initial position in which the zero numeral of the characters D will appear at the observation opening 19. The units column of figures is then added as follows:—The pin 22 is inserted in the hole 18 next adjacent to the digit in the row E corresponding to the first figure in the units column of the numbers to be added. The disk is then turned by the pin 22 until the pin strikes the lower end of the slot 19. This pin 22 is then withdrawn, after a similar pin has been inserted in the hole which is next adjacent to the digit representing the

unit next above, in the column which is being added. This form of my invention is adapted for adding single columns of figures. When all the figures in the column have been added, as above described, the sum will appear at the observation opening 19. If it be found that the number at that opening is more than 100, for example, 105, and there are other figures yet to be added, the pin 21 is inserted in the hole 20 which is adjacent to the digit 1. The disk 17 is then advanced to a position in which the numeral 5 will appear at the observation opening 19. The addition will then be continued in the manner just above described. The sum of the column will be represented by what is shown in the observation opening 19, taken in connection with the indication in the row of holes 20.

It will be noted that in the form of invention shown in Fig. 4, and also that shown in Fig. 8, there is provided on the disk an imperforate space between the zero numeral hole and the hole designated by the numeral 109. The provision of this imperforate space prevents the operator from unconsciously making an error in addition, when in the operation of the machine, the amount added by the disk exceeds 109. The operation being merely mechanical, and the operator, in adding the column merely noting the figure in the column which he is to add, and paying no attention to the total which has been added, is liable to make an error, providing that the imperforate space above referred to were not present, there being no means provided if the imperforate space were omitted, to call his attention to the fact that a hundred had been added and should be indicated in the row of holes 11, in the form shown in Fig. 2, and in the row of holes 20 in the form shown in Fig. 6. The length of the imperforate space between the zero hole and the 109 hole is greater than the distance covered by any ten holes in the disk. When the disk has been turned so that 109 would be indicated, the operator, unconscious of this indication, in continuing his addition of the column, would find that no hole would be opposite any one of the numerals E, Fig. 6, or opposite the numerals B, Fig. 2, the imperforate space, in each case, being opposite to these rows of numerals. This would call his attention to the fact that the disk had added 100 or more, and he would then make the indication with the pin 12 in the holes 11, Fig. 1, or with the pin 21 in the holes 20, Fig. 6. He would then advance the disk, in the manner already described, to a position in which the numeral appearing at the observation opening will appear at such opening, following which he will continue the addition of the column in the manner already described. If the slot 2, Fig. 2, and the slot 19, 189

- Fig. 6, are of the proper length, that is, the length of the imperforate space added to the distance covered by 10 holes in the disk, the machine may be operated, by inserting 5 the operating pin in the hole at the upper end of the slot, then by removing the lower pin in the slot and advancing the disk the proper numeral will appear at the observation opening.
- 10 I do not limit my invention to the structures shown and described, as various modifications may be made, within the scope of the appended claims, without departing from the spirit of my invention.
- 15 What I claim is:
1. In an adding machine, a casing having an arcuate slot, an observation opening, characters comprising the digits arranged in a row at one side of said slot, and a rotary disk in said casing having one hundred and ten holes adapted to receive a stop pin inserted through said slot and spaced apart from each other at the same distance as the distance between the digits, the disk being 20 provided with a series of numerals from zero to one hundred and nine inclusive arranged so as to pass consecutively in front of said observation opening, the disk being disposed concentric with said slot and provided with an imperforate space between the terminal holes respectively designated by zero and 109, said space exceeding in 25 length the distance covered by ten holes in the disk.
  2. In an adding machine, a casing having a slot, an observation opening and characters comprising the digits arranged in a row at one side of said slot, and a rotary disk in said casing having a series of peripheral 30 holes adapted to receive a stop pin inserted 35

through said slot and spaced apart to correspond with said digits, the periphery of said disk between the ends of said series being provided with a blank space for indicating the maximum indication.

45

3. In an adding machine, a casing having a slot, an observation opening and characters comprising the digits arranged in a row at one side of the slot, and a rotary disk in said casing having a series of peripheral holes adapted to receive a stop pin inserted through said slot and spaced apart to correspond with the digits, the periphery of said disk between the ends of said series being provided with a blank space for indicating the 50 maximum indication, said slot in length corresponding to the space occupied by said blank space and ten of the holes in said disk.

55

4. In an adding machine, a casing having a slot adapted to receive therethrough a stop pin, an observation opening and a row of characters comprising the digits arranged parallel with the slot, and a rotary disk in said casing having a circularly arranged row of one hundred and ten holes spaced apart 60 to correspond with said digits and adapted to receive a stop pin.

60

5. In an adding machine, a casing having a slot adapted to receive therethrough a stop pin and a row of characters comprising the 70 digits arranged parallel with the slot, and a movable member mounted in said casing and having a row of one hundred and ten holes spaced apart to correspond with said digits and adapted to receive a stop pin inserted 75 through said slot.

70

In testimony whereof I have signed my name to this specification.

ARTHUR R. BALL.
